UNITED STATES PATENT OFFICE.

WILLIAM T. FLETCHER, OF BELFAST, IRELAND.

RECIPROCATING-FLAT-BED WEB-PRINTING MACHINE.

1,094,386.

Specification of Letters Patent. Patented Apr. 21, 1914.

Application filed April 20, 1912. Serial No. 692,118.

To all whom it may concern:

Be it known that I, WILLIAM THOMAS FLETCHER, a citizen of the United Kingdom of Great Britain and Ireland, whose post-office address is 58 Brookvale avenue, Antrim Road, Belfast, in the county of Antrim, Ireland, have invented a new Model of Printing-Machine—viz., a Reciprocating-Flat-Bed Web-Printing Machine—of which 10 the following is a specification.

The object of this invention is to print on one or both sides of a continuous web of paper from flat forms and at a speed quicker than can be attained by feeding 15 separate sheets of paper into a machine.

The nature of the invention is to still retain the flat reciprocating bed commonly used on printing machines, but to substitute for the single cylinder in general use a set 20 of four cylinders so that the machine shall print on both strokes of the bed, first by one pair of cylinders and then by the other pair. The cylinders are adapted to work in pairs to permit two pages to be printed 25 simultaneously, thus the travel of the bed is reduced by one half and the speed increased.

The accompanying drawing is a vertical elevation of the entire machine, showing one 30 side frame removed for convenience of illustrating the bed-motion and method of gearing the cylinders.

The following detailed description has reference to the drawing and will show how 35 I attain these objects:

Two impression cylinders (A and B) revolving continuously in the one direction are arranged in juxtaposition to print on one side of a continuous web of paper (E) from 40 forms arranged in four sets of two, three, or four according to the number of pages to be printed on a flat reciprocating form bed (F) on the outward stroke. The second cylinder (B) prints on that portion of the 45 web missed by the first cylinder (A) on the backward stroke of the form-bed.

And two impression cylinders (C and D) revolving continuously in the one direction, but opposite direction to said two previous 50 cylinders are arranged in juxtaposition to print on one side of said continuous web of paper (the reverse side of web mentioned in previous paragraph, and thus perfect) from the same flat reciprocating bed on the 55 backward stroke. The second cylinder (D) prints on that portion of the web missed by

the first cylinder (C) on the outward stroke of the form-bed.

To permit of the backward stroke of the form all the cylinders are of two radii. The 60 half of the periphery used for the impression having a greater radius than the other half. On the return stroke of the bed the form passes beneath the smaller radius of the cylinder without coming into contact therewith.

The pinion on the central shaft is adapted 65 to engage alternately with an upper and a lower rack on the bed to reciprocate the same, and the cylinders are continuously rotated by a train of gearing connected with said central shaft. The bed is reversed in the usual well known manner of bed and cylinder machines.

Between the cylinders and raised above 70 them are carrying rollers, these serving to deliver the web from one cylinder to another in such a position that the portions missed by the cylinder A or C are printed by the cylinders B. or D. respectively.

When only one side is to be printed the first two cylinders are used, the paper traversing the other cylinders, there being then no forms on that side of the machine.

I am aware that prior to my invention 85 flat-bed web-fed printing machines have been made. I therefore do not claim such a combination broadly, but

I claim—

1. In a printing press the combination of 90 four cylinders with one flat reciprocating form bed having four sets of forms thereon co-acting with said cylinders, each cylinder co-acting with a single set of forms, means for rotating the cylinders continuously, two 95 of said cylinders in the direction of the forward stroke of the form-bed and the other two cylinders in the direction of the return stroke of the form-bed, both cylinders and bed operated from a central shaft, the cylinders operating to print on both sides of a continuous web and said cylinders also operating to feed the web continuously between the bed and cylinders both during the forward and return strokes of the form-bed.

2. In a printing press the combination of 100 two pairs of cylinders with one flat reciprocating form bed having four sets of forms thereon, each cylinder co-acting with a single set of forms, the cylinders of each pair rotating in the same direction and oppositely to the cylinders of the other pair, each of

said cylinders being provided with an impression surface of one radius for coaction with its set of forms on one stroke of said bed and also provided with a non-impression surface of a less radius to avoid engagement with said bed on the opposite stroke thereof, means for rotating said cylinders continuously said cylinders and bed being operated from a central shaft, said impression sur-

faces coöperating with said form bed to print on both sides of a continuous web and said cylinders also operating to feed the web continuously between the bed and cylinders during both strokes of said bed.

W. T. FLETCHER.
